VENETIAN BLIND HOLD-DOWN BRACKET

Harry Nelson, New York, N. Y., assignor to
 Lorentzen Hardware Mfg. Corp., New York,
 N. Y., a corporation of New York

Application February 4, 1947, Serial No. 726,355

2 Claims. (Cl. 248—267)

1

This invention relates to a construction for holding down a Venetian blind when it is fully extended, to prevent the blind from slapping in the wind. Embraced within the invention is a hold-down bracket for mounting on the window frame to hold the blind down, the bracket being adapted for both "inside" and "outside" mounting of the blind. An "inside" mounting is one in which the blind is nested within the window opening, the hold-down brackets being usually mounted on the sill of the window. An "outside" mounting is one in which the blind is not nested within the window opening; usually the end of the slats overlie the faces of the window jambs, and the hold-down brackets are usually mounted on the face of the window frame which faces the room.

Various hold-down constructions and brackets are already known, one form now in extensive use being that shown in Lorentzen U. S. Patent 2,298,892 dated October 13, 1942. The hold-down bracket of that patent can be mounted with all parts of the bracket positioned close to the side of a window jamb; and, as compared to certain prior brackets, it effected considerable improvement from the standpoint of interfering with dusting and cleaning and likelihood of catching on the clothing of persons moving close to the window. However, the bracket of that patent is somewhat more advantageous when the blind is mounted "inside" than it is when the blind is mounted "outside."

A hold-down bracket which is very desirable from the standpoint of freedom from any substantial tendency to snag dusters, wiping cloths, and clothing, is shown in my U. S. Patent 2,402,769 dated June 25, 1946. However, with that bracket it is not quite as easy to insert a mounting screw through the foot of the bracket as it is with the bracket shown in Patent 2,298,892. Also, the bracket of my Patent 2,402,769 has a somewhat unconventional appearance.

A general object of the present invention is to provide a Venetian blind hold-down construction, including a hold-down bracket, which to a considerable degree realizes the advantages of both the bracket of Patent 2,298,892 and the bracket of Patent 2,402,769.

Among specific objects of the invention are 50 to provide a hold-down bracket which may be mounted on a window sill with all upwardly-projecting portions quite close to the jamb, which has little tendency to snag clothing and cleaning cloths, which is suitable for both left-

hand and right-hand mounting, which is advantageous when the blind is mounted "outside" as well as "inside," which is inexpensive to produce, which is rugged in use, and which may be advantageously manufactured as a one-piece sheet metal stamping.

Further objects, and objects relating to details and economies of manufacture, installation and use will more definitely appear from the detailed description to follow.

My invention is clearly defined in the appended claims. In the claims, as well as in the description, parts are at times identified by specific names for clarity and convenience, but such nomenclature is intended to be as generic, in its application to similar parts, as the concept of my invention in relation to the pertinent prior art will permit. The best form in which I have contemplated applying my invention is illustrated in the accompanying drawing forming a part of this specification, in which:

Fig. 1 is a fragmentary front elevation showing a window frame with an "inside"-mounted Venetian blind held down by brackets of the present invention mounted on the sill.

Fig. 2 is a side elevation, partially in section, showing on a large scale one of the duplicate hold-down brackets shown in Fig. 1.

Fig. 3 is a front elevation of the bracket shown in Fig. 2, the cooperating pin of the blind being indicated in dot-dash lines.

Fig. 4 is a top plan view of the bracket shown in Fig. 2.

Fig. 5 is a fragmentary front elevation, to a smaller scale than Figs. 2-4, showing the bracket of Figs. 2-4 mounted on the front face of a window frame for cooperation with a blind that is mounted "outside." A portion of the bottom bar of the blind is indicated in dot-dash lines.

Fig. 6 is a fragmentary sectional view on the line 6—6 of Fig. 5, the bottom bar of the blind being indicated in dot-dash lines.

The window frame 10 shown in Fig. 1 includes jambs at 11, 11, the faces of which extend perpendicularly to the plane of the figure. The bottoms of the jambs are connected by a sill 12. Vertical trim pieces 14, 14 extend across and beyond the front edges of the jambs, and a horizontal trim piece 15 extends beneath the front portion of the sill. The parts 11, 12, 14 and 15 are all considered as being part of the window frame. In some window constructions, the sill does not project into the room beyond the plane of the wall surface, and trim pieces such as 14 and 15 are omitted. Such a window is

shown fragmentarily in Figs. 5 and 6; and with such a window, the frame thereof is considered to include a several inch wide wall zone which embraces the window opening.

Suspended "inside" the window frame 10 is a Venetian blind designated as a whole by 16. The bottom bar or rail 17 of the blind is provided, by fittings or otherwise, with pins 18, 18 which project from the ends thereof perpendicularly toward the faces of the jambs at 11, 11. Secured to the sill 12 are hold-down brackets 19, 19 which receive the pins and thereby hold the blind down.

The brackets 19, 19 are duplicates, each being of the form shown in Figs. 2, 3 and 4. Each bracket 19 is preferably formed as a one-piece sheet metal stamping. I prefer to stamp the bracket from mild sheet steel, suitably plated or otherwise rust-proofed, either before or after stamping.

The bracket 19 has a base 20 which includes a body portion 21 and an arm portion 22 extending therefrom. When the bracket is mounted on a flat surface, both the body portion 21 of the base and the arm portion 22 thereof engage the surface on which the bracket is mounted. The base is elongated, having on opposite sides long edges 24 and 25. Body portion 21 of the base is provided with a hole 26 to receive a headed fastener, such as a screw 27 (Figs. 5 and 6), preferably a conventional flat-headed screw. Struck from the base 20 are a pair of prongs 28, 28 which penetrate the surface on which the bracket is mounted, thereby preventing swivel movement of the bracket about the mounting screw 27. Metal surrounding the hole 26 is embossed to form an upstanding annular rib 29. This rib stiffens and strengthens the base and eliminates the necessity for countersinking to provide a seat for the tapered head of a flat-headed screw.

Arm portion 22 of the base 20 is also bossed to form an upstanding rib 30, this rib merging with annular rib 29. The rib 29 stiffens and strengthens the arm portion 22, particularly in its connection to the body portion 21 of the base.

One edge of arm portion 22 coincides with edge 25 of the base. However, the opposite edge of arm portion 22 is aligned with a point substantially half way between edges 24 and 25. Extending from this edge of arm portion 22, and integrally connected with the arm portion, is a flat pin-retaining member 31.

The pin-retaining member 31 is a flat piece of sheet metal extending perpendicularly to the general plane of base 20, the sheet formation of member 31 lying in a plane which is midway between two planes parallel thereto and containing, respectively, edges 24 and 25 of the base. The member 31 is adapted to receive and retain a pin, such as pin 18, projecting from the end of the bottom bar of a blind. For this purpose member 31 is provided with a slot 32 as shown, to receive the pin. The slot results in the pin-retaining member 31 having a hook portion at 34.

Locating the pin-retaining member 31 as shown midway between edges 24 and 25, imparts to the bracket two advantageous characteristics. Firstly, when mounted as shown in Fig. 1, the upwardly-projecting part of the bracket is spaced laterally from the side of the jamb by an amount which is only half of the width of base 20. Secondly, this spacing is the same whether edge 24 or edge 25 be placed against the face of the

jamb. This not only permits the same bracket to be mounted either on the left-hand or right-hand side of the window frame, but permits it to be mounted (on an inside mounting) with the hook 34 either toward the room or toward the window.

Figs. 5 and 6 show the bracket installed for an "outside" mounting of the blind, the base 20 of the bracket being secured to the face 35 of the window frame, and the pin-retaining member 31 projecting toward the room. In these figures there is indicated a bottom bar 36 in the end of which there is driven a gudgeon pin 37 which is received by the slot 32.

It will be noted that whether the bracket be used for an "inside" mounting or an "outside" mounting, it will be necessary to depress the bottom bar of the blind, stretching the ladder tapes, before the pin can be inserted into the slot 32. Once the pin is inserted, the ladder tapes resiliently draw the pin to the blind end of the slot, thereby preventing accidental disengagement of the pin from the slot.

The bracket can be rapidly and economically stamped in one piece from sheet metal, with a relatively small amount of scrap. Edge 40 (Fig. 4), as well as edge 41 (Fig. 2), may be the edge of a strip of material from which the bracket is stamped.

I claim:

1. A Venetian blind hold-down bracket formed as a one-piece sheet metal stamping, said bracket comprising: a base including a body portion having oppositely positioned longitudinal edges, said base also including an arm portion extending from one end of the body portion in the same general plane as the body portion, one longitudinal edge of the arm portion being substantially in prolongation of the longitudinal center line of said body portion, a flat pin-retaining member disposed perpendicularly to said base and being integrally connected with said one longitudinal edge of said arm portion, said pin-retaining member being provided with a pin-receiving slot extending upwardly and inwardly from that edge of the pin-retaining member which is remote from the body portion of the base, the body portion of the base having a single hole to receive a headed fastener, the axis of the hole lying on the longitudinal center line of the body portion of the base and the metal surrounding the hole being embossed into an upstanding annular rib, metal of the arm portion being embossed into an upstanding rib extending lengthwise of the arm portion and merging tangentially with said annular rib which surrounds the hole that receives the headed fastener, and at least one metal formation extending downwardly from said base to engage the surface on which the bracket is mounted and oppose swivel movement of the bracket about a fastener passing through said hole.

2. A Venetian blind hold-down bracket formed as a one-piece sheet metal stamping, said bracket comprising: a base including a body portion having oppositely positioned longitudinal edges, said base also including an arm portion extending from one end of the body portion in the same general plane as the body portion, one longitudinal edge of the arm portion being substantially in prolongation of the longitudinal center line of said body portion, a flat pin-retaining member disposed perpendicularly to said base and being integrally connected with said one longitudinal edge of said arm portion, said pin-retaining mem-

ber being provided with a pin-receiving slot extending upwardly and inwardly from that edge of the pin-retaining member which is remote from the body portion of the base, the body portion of the base having a single hole to receive a headed fastener, the axis of the hole lying on the longitudinal center line of the body portion of the base and the metal surrounding the hole being embossed into an upstanding annular rib, metal of the arm portion being embossed into an upstanding rib extending lengthwise of the arm portion and merging tangentially with said annular rib which surrounds the hole that receives the headed fastener.
